UNITED STATES PATENT OFFICE.

ARTHUR E. STACHEL, OF CHICAGO, ILLINOIS.

CYLINDER-COCK.

1,126,900.

Specification of Letters Patent.

Patented Feb. 2, 1915.

Application filed May 18, 1914. Serial No. 839,306.

To all whom it may concern:

Be it known that I, ARTHUR E. STACHEL, a citizen of the United States, residing at Chicago, in the county of Cook and State of Illinois, have invented certain new and useful Improvements in Cylinder-Cocks, of which the following is a specification.

This invention relates to cylinder cocks employed for draining the cylinders of locomotive engines, and its object is to provide a novel and improved mechanism for effecting an automatic operation of the cocks, as well as means whereby the cocks may be controlled manually.

15 The invention consists in a combination and arrangement of parts producing certain new and useful results to be described hereinafter in detail.

In order that the invention may be better understood, reference is had to the accompanying drawings, in which—

Figure 1 is an elevation of the apparatus partly in section; Fig. 2 is a vertical section of a water-relief valve; Fig. 3 is a vertical section of a manually operated controlling valve, and Fig. 4 is a vertical section of a check valve.

Referring specifically to the drawings, 10 denotes one of the cylinders of a locomotive 30 having bottom ports 11 at its ends to which are connected cylinder-cocks 12 for draining the cylinder of water. The cocks are operated by a longitudinally slid able stem 13 in the ordinary manner, and as no novelty 35 is claimed for these parts, a further description thereof is deemed unnecessary.

At 14 is indicated a cylinder in which is slidably mounted a plunger 15 having a rod 16 which extends from both sides of the 40 plunger and passes through stuffing boxes 17 on the heads or ends of the cylinder. One end of the rod 16 is operatively connected in any suitable manner to the stem 13, and its other end extends into a cylinder 45 18 and is connected to a plunger 19 working therein. The cylinder 18 serves as a dash-pot to retard the movement of the plunger 15, for a purpose to be presently described. The cylinder 18 is adapted to be filled with 50 oil, and open communication between opposite ends of the cylinder is established by means of a conduit 20 in which a regulating valve 20^a is interposed.

The cylinder 14 has fluid-pressure inlets

21 and 22, respectively, at its ends. A conduit 23 leading from the exhaust port 24 of the cylinder 10 is connected to the inlet 21. To the inlet 22 is connected a conduit 25. To the conduit 23 is connected a conduit 26. In the conduit 23, between the port 24 and 60 the junction of the conduit 26 with said conduit 23, is a spring seated drain valve 27 and a check valve 28, the latter having a small bleed port 29.

The conduits 25 and 26 extend from a valve comprising a casing 30 having outlets 31 and 32, respectively. The conduit 25 is connected to the outlet 31, and the conduit 26 is connected to the outlet 32. Between these outlets is an inlet 33 to which is connected a conduit 34 leading from a compressed air reservoir 35, which may be the main reservoir of the air-brake system. In the casing 30 works a turning plug 36 which is constructed to establish communication 75 between the inlet 33 and either one of the outlets 31 and 32. Normally, the plug covers both outlets and it is held in this position by springs 37 engaging the handle 38 of the plug. Upon swinging the handle 80 to one side, the plug establishes communication between the inlet and one of the outlets, and when the handle is swung over to the other side, communication is established between the inlet and the other outlet. When 85 the handle is released, the springs restore it to neutral position to close both outlets.

The cylinder 14 contains a spring 39 which engages one side of the plunger 15 and serves to force the same toward one end 90 of the cylinder. On that side of the plunger which is engaged by the spring, the cylinder 14 has a vent port 40.

The end of the cylinder 10 is connected by a conduit 41 to an automatic water relief 95 valve comprising a casing 42 in which works a plunger 43 having a stem 44 which carries a valve 45 the area of which latter is less than that of the plunger. The casing contains a seat 46 for the valve 45, and the conduit 41 enters the casing on one side of the seat. On the other side of the valve seat, the casing has an outlet 47 from which a conduit 48 extends to and joins the conduit 25. The outlet 47 is located between the 105 valve 45 and one side of the plunger 43, and on the other side of said plunger, the valve casing has a fluid-pressure inlet 49 connect-

ed by a conduit 50 to the live steam port of the cylinder 10.

The operation of the apparatus hereinbefore described may be summarized as follows: The normal position of the plunger 15 is adjacent to that end of the cylinder 14 having the inlet 21, to which position it is forced by the spring 39. When the plunger moves to this position, the stem 13 is actuated to open the cocks 12. When the throttle is opened to admit steam to the cylinder 10, the exhaust steam passes through the conduit 23 and enters the cylinder 14 by the way of the inlet 21, whereupon the plunger 15 is forced forward against the tension of the spring 39 and the resistance offered by the dash-pot 18. This movement of the plunger actuates the stem 13 to close the cocks 12. The rate of speed at which the plunger 15 travels is reduced by the dash-pot 18 which can be regulated by the valve 20^a. The cylinder cocks therefore close slowly and sufficient time is allowed for the escape of water from the cylinder 10. When the throttle is closed to shut off the steam supply to the cylinder 10, the exhaust pressure ceases to act against the plunger 15, whereupon the spring 39 returns it to open the cocks 12. Here again the movement of the plunger is retarded by the dash-pot so that the cocks will not open too soon.

The operation of the cylinder cocks 12 may also be controlled manually in the following manner: In starting the locomotive, if for any reason it is desired to close the cylinder cocks quickly, the valve handle 38 is swung to admit compressed air behind the plunger 15 by the way of the conduits 26 and 23, through the inlet 21. The air, by reason of its greater pressure than the exhaust pressure, will move the plunger quickly in a direction to close the cylinder cocks. The cocks may also be closed in this manner while the locomotive is standing at passenger stations. When the valve handle 38 returns to neutral position, the air which was admitted to the cylinder 14 bleeds off slowly through the bleed port 29 in the check valve 28, into the conduit 23, and this, together with the dash-pot, will hold the cylinder cocks closed for short stops at passenger stations. While running, the cylinder cocks are normally closed, and should the engineer desire to open the same, he would need only to admit air into the cylinder 14 through the conduit 23 and the inlet 22. This pressure will exceed the exhaust pressure which has advanced the plunger 15, and the latter is therefore returned to opening position. The valve handle 38 automatically returns to neutral position when it is released, and in this position, the plunger 15 is operated automatically, keeping the cylinder cocks closed

while the locomotive is running, and opening the same when standing. The exhaust of the air admitted into the cylinder 14 through the inlet 22 is through the vent port 40, which latter also allows water to be drained out of said cylinder. The drain valve 27 is designed for the purpose of keeping that part of the system drained of water. The check valve 28 retains the air which is admitted into the cylinder 14 through the inlet 21. The bleed port 29 is open at all times and keeps the plunger 15 from being air-bound, which would prevent the automatic operation hereinbefore described.

The purpose of the water-relief valve is to automatically effect the opening of the cylinder cocks 12 if water should accumulate in the cylinder 10 when running. The operation is as follows: Normally, the plunger 43 holds the valve 45 to its seat 46 by reason of the live steam pressure on top of the plunger, and the fact that the area of the plunger is greater than the area of that portion of the valve which is exposed to the pressure in the cylinder 10. When water accumulates in the cylinder the abnormal pressure created at the ends of the stroke of the piston working therein, will unseat the valve 45, the pressure passing through the conduit 41 into the valve casing 42 beneath the valve 45. This pressure then escapes through the outlet 47 and passes through the conduit 48 into the cylinder 14, and forces the plunger 15 in a direction to open the cylinder cocks 12. When the excessive pressure is relieved, the plunger 43 is forced down by the live steam pressure thereagainst, and the valve 45 is reseated.

The advantages of the apparatus will be readily manifest to those skilled in the art to which it pertains. The cylinder cocks can be operated from the cab of the locomotive by the engineer without interfering with the automatic operation, and the cylinder cocks will be opened automatically when the locomotive is at rest, and when the locomotive is started, they will be closed automatically after the desired interval of time, which may be varied by the valve 20^a. The engineer cannot leave the locomotive and let the cylinder cocks remain closed, as they will be opened automatically when steam is shut off. A leaky throttle has no effect on the cylinder cocks and they will open and remain open at the proper time. The automatic water-relief valve prevents damage of the cylinder by water when running. The automatic features cannot be rendered inoperative by the manually controlled devices as the valve handle 38 is normally in neutral position. The cylinder cocks will positively be open when the locomotive is in the engine house, and they will open even though forgotten by the hostler,

and in taking the locomotive out the cylinder cocks are sure to be open. It will also be apparent that the apparatus can be readily applied to any common type of cylinder cocks.

I claim:

1. The combination with a steam engine cylinder having cylinder cocks, and operating means for said cocks; of means for actuating said operating means, said actuating means comprising a cylinder, a plunger working in the cylinder, a rod extending from the plunger and operatively connected to the aforesaid operating means, a fluid-pressure inlet to the last-mentioned cylinder for moving the plunger in a direction to close the cylinder cocks, a dash pot for retarding the travel of said plunger in this direction, and means for operating the plunger to open the cylinder cocks.

2. The combination with a steam engine cylinder having cylinder cocks, and operating means for said cocks; of means for actuating said operating means, said actuating means comprising a cylinder, a plunger working in the cylinder, a rod extending from the plunger and operatively connected to the aforesaid operating means, a fluid-pressure inlet to the last-mentioned cylinder for moving the plunger in a direction to close the cylinder cocks, means for returning the plunger to open the cylinder cocks, and means for retarding the travel of the plunger in both directions to delay the opening and the closing movement of the cylinder cocks.

3. The combination with a steam engine cylinder having cylinder cocks, and operating means for said cocks; of means for actuating said operating means, said actuating means comprising a cylinder, a plunger working in the cylinder, a rod extending from the plunger and operatively connected to the aforesaid operating means, fluid-pressure inlets to the last-mentioned cylinder on opposite sides of the plunger for moving the plunger to actuate the aforesaid operating means, a manually operated valve controlling said fluid-pressure inlets, and means for leading exhaust steam from the engine cylinder into the last-mentioned cylinder to move the plunger in a direction to close the cylinder cocks.

4. The combination with a steam engine cylinder having cylinder cocks, and operating means for said cocks; of means for actuating said operating means, said actuating means comprising a cylinder, a plunger working in the cylinder, a rod extending from the plunger and operatively connected to the aforesaid operating means, fluid-pressure inlets to the last-mentioned cylinder on opposite sides of the plunger for moving the plunger to actuate the aforesaid operating means, a manually operated valve control-

ling said fluid-pressure inlets, a conduit for leading exhaust steam from the engine cylinder into the last-mentioned cylinder to move the plunger in a direction to close the cylinder cocks, and a check valve in said conduit.

5. The combination with a steam engine cylinder having cylinder cocks, and operating means for said cocks; of means for actuating said operating means, said activating means comprising a cylinder, a plunger working in the cylinder, a rod extending from the plunger, and operatively connected to the aforesaid operating means, fluid-pressure inlets to the last-mentioned cylinder on opposite sides of the plunger for moving the plunger to actuate the aforesaid operating means, a normally operated valve controlling said fluid-pressure inlets, a conduit for leading exhaust steam from the engine cylinder into the last-mentioned cylinder to move the plunger in a direction to close the cylinder cocks, and a check valve in said conduit, said check valve having a bleed port.

6. The combination with a steam engine cylinder having cylinder cocks, and operating means for said cocks; of means for actuating said operating means, said activating means comprising a cylinder, a plunger working in the cylinder, a rod extending from the plunger and operatively connected to the aforesaid operating means, fluid-pressure inlets to the last-mentioned cylinder on opposite sides of the plunger for moving the plunger to actuate the aforesaid operating means, a manually operated valve controlling said fluid-pressure inlets, means for automatically returning said valve to neutral position, and means for leading exhaust steam from the engine cylinder into the last-mentioned cylinder to move the plunger in a direction to close the cylinder cocks.

7. The combination with a steam engine cylinder having cylinder cocks, and operating means for said cocks; of means for actuating said operating means, said activating means comprising a cylinder, a plunger working in the cylinder, a rod extending from the plunger and operatively connected to the aforesaid operating means, a water relief valve casing connected to the ends of the steam engine cylinder and having an outlet into the second mentioned cylinder, a valve in said casing exposed on one side to the pressure in the steam engine cylinder, and a plunger carrying the valve, said plunger being exposed to the live steam pressure in the engine cylinder.

8. The combination with a steam engine cylinder having cylinder cocks, and operating means for said cocks; of means for actuating said operating means, said activating means comprising a cylinder, a plunger

working in the cylinder, a rod extending from the plunger and operatively connected to the aforesaid operating means, means for leading exhaust steam from the engine cylinder into the last-mentioned cylinder to move the plunger in a direction to close the cylinder cocks, and normally inoperative and manually controlled means for admitting fluid-pressure into said cylinder to

effect the manual control of the cylinder 10 cocks.

In testimony whereof I affix my signature in presence of two witnesses.
